US00D886428S

(12) **United States Design Patent** (10) Patent No.: **US D886,428 S**
(45) Date of Patent: ** Jun. 9, 2020

(54) **SHOE SOLE**

(71) Applicant: **TBL Licensing LLC**, Stratham, NH (US)

(72) Inventors: **Anna Regan Natowich McPhee**, Durham, NH (US); **Norman Gress**, Andover, MA (US); **Allison Sinclair Johnson**, Epping, NH (US)

(73) Assignee: **TBL Licensing LLC**, Stratham, NH (US)

(**) Term: **15 Years**

(21) Appl. No.: **29/632,477**

(22) Filed: **Jan. 8, 2018**

(57) **CLAIM**

The ornamental design for a shoe sole, as shown and described.

DESCRIPTION

FIG. 1 is a bottom perspective view of a shoe sole according to our design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate unclaimed environmental structure and form no part of the claimed design.

1 Claim, 6 Drawing Sheets
